[57] CLAIM

The ornamental design for a table, as shown and described.

DESCRIPTION

FIG. 1 is a front perspective view of a table showing my new design;

FIG. 2 is a side elevational view thereof;

FIG. 3 is a front elevational view thereof;

FIG. 4 is a top plan view thereof;

FIG. 5 is a bottom plan view thereof;

FIG. 6 is a perspective view of an alternative table embodying the particular corner configuration of FIG. 1; and

FIG. 7 is a perspective view of a further alternative table embodying the particular corner configuration of FIG. 1.

The table is characterized by the particular configuration of the corners thereof as shown.
